UNITED STATES PATENT OFFICE.

JAMES CARRIE, OF BUTLER, PENNSYLVANIA, ASSIGNOR TO PLATE GLASS MACHINERY CO., OF BUTLER, PENNSYLVANIA.

MACHINE FOR GRINDING AND POLISHING SLABS.

Application filed March 10, 1924. Serial No. 698,066.

To all whom it may concern:

Be it known that I, JAMES CARRIE, a citizen of Great Britain, and resident of Butler, in the county of Butler and State of Pennsylvania, have invented certain new and useful Improvements in Machines for Grinding and Polishing Slabs; and I do hereby declare that the following is a full, clear, and exact description thereof.

10 My invention refers to new and useful improvements in machines for grinding and polishing slabs, such, for example, as glass or the like, particularly applicable to machines, such as disclosed in my patents 15 for polishing machines, Number 1,375,129, dated April 19, 1921, and Number 1,430,214, dated September 26, 1922. The particular object of my present invention is to grind and polish plates of glass uniformly 20 throughout their area and at the same time, complete such grinding and polishing in the minimum space of time. In actual reduction to practice, with reference to my previous polishing and grinding machines, it 25 developed in polishing that the central area of the plates of glass were quickly polished, but the outer edges of the plates required more time to reduce them to the same degree of polish as the intermediate field.

30 In the patents referred to above, the polishing and grinding apparatus, in practice, has been installed in fixed position and plate carriers or cars have been caused to travel under the burnishing and polishing shoes, 35 which shoes were subjected to a planetary movement. It was noted, as previously stated, that the longitudinal center of the glass, (figured in the direction of travel of the carriage,) was more quickly polished 40 than the outer edges, due to the fact that the polishing units travel across the imaginary central line of the glass more often in the course of operation, than they travel over the edges. This is caused, in other 45 words, by the development of a planetary movement of the polishing shoes in conjunction with the longitudinal travel of the carriage carrying the plates of glass. The above noted unevenness in polishing of the 50 longitudinal center or field of the glass plate to its outer edges, has been overcome by an advance in the art, to which my present invention refers, which advance embodied the application of an additional series of grinding and polishing shoes, dis-

posed between a group of planetary driven shoes. The auxiliary shoes, so disposed, being mounted upon idle spindles, whereby the motion imparted thereto, is due only to the rotation of the main head. With 60 the above and other objects in view, the invention consists in certain peculiarities of construction and combination of parts as will be hereinafter set forth in reference to the accompanying drawings, and subse- 65 quently claimed.

In the drawings, Figure 1 represents a diagrammatic view in elevation of a grinding and polishing machine, embodying the features of my present invention, parts being broken away in sections to more clearly illustrate details of construction.

Figure 2 represents a plan sectional view, the section being indicated by line 2—2 of Figure 1.

75 Figure 3 represents a plan view of modified form of shoe.

Referring by characters to the drawings, 1 represents a suitable frame, which carries bearings and supports for a main shaft 2, 80 there being means for vertically adjusting the shaft, and a gear wheel 3 for rotating the same, all of which mechanism constitutes no part of my present invention.

The main drive shaft 2 has secured thereto a master head 4 and rigidly secured to the sleeve of the non-rotary supporting frame 1 is a master gear wheel 5. This gear wheel 5 is meshed with a series of intermediate gear wheels 6, which latter 90 gear wheels impart drive to pinions 7, that are fastened on vertically disposed auxiliary drive shafts 8, the same being journalled in the master head 4.

95 Each auxiliary drive shaft 8 has secured to its lower end an auxiliary skeleton head 9 provided with a series of vertically disposed bearings for groups of spindles 10, as best shown in Figure 2.

These spindles 10 are adapted to revolve 100 idly and their lower end has secured thereto, grinding and polishing shoes 11.

It will be noted that all the parts, just described, are in substance similar to the machines disclosed in my previous inventions mentioned with the exception that the groups of auxiliary shoes are not positively driven as is the case in the shoes disclosed in my Patent No. 1,430,214.

110 The master head, which carries the gears

for imparting planetary movement to the groups of polishing and grinding shoes 11, is provided with suitable gear case or housing 12.

- 5 Secured to the master head 4, by brackets 13, are a series of journalled boxes 14, which journalled boxes form bars for auxiliary spindles 15. These auxiliary spindles carry auxiliary grinding and polishing shoes 16.
- 10 The auxiliary or edge grinding and polishing shoes 16, as best shown in Figure 2 of the drawings, are disposed approximately upon the same major peripheral or circular plane, as the groups of grinding and polishing shoes 11 and they are radially positioned between each group of shoes.

As shown in Figure 1, the glass plate 17, is suitably mounted upon and secured to a longitudinal traveling table 18, which table 20 is supported by truck wheels, adapted to traveling upon tracks 19. Thus, as indicated by an arrow in Figure 2, the table carrying the glass plate, will travel longitudinally with reference to the fixed center 25 of motion of the groups of grinding and polishing shoes.

From the foregoing description, it will be seen that when the master head 4 is put into motion, the groups of grinding and 30 polishing shoes 11, will through their gear connection, cause said groups to develop a planetary motion. At the same time, the auxiliary edge polishing and grinding shoes 16 will simply develop a rotary motion with 35 respect to the axes of the machine, and the auxiliary shoes will, of course, rotate independently, which rotation is imparted thereto, due to the traveling of the mechanism only.

40 The rotation of the shoes 11 is also developed in the same manner and is, of course, independent of any positive drive. Thus it will be seen that all the shoes rotate upon their axes independently of any positive drive mechanism, whereby the plate of 45 glass is more evenly and more effectually polished to the desired degree, and owing to this construction, by actual test, it has been found that the glass, when polished 50 to the desired degree, is practically of uniform thickness. In other words, the tendency of the glass to grinding or polishing, more readily at the longitudinal center of the carriage, is overcome, whereby the edges 55 of the glass, as indicated at X, Figure 2, are practically ground to the desired degree in

the same space of time, as the center of the glass. The extra polishing of the edges of the glass being effected by the application of the idle polishing and grinding shoes 16. 60

While I have shown and described one exemplification of my invention, wherein the edge grinding shoes 16 are arranged centrally with relation to their carrying spindles 15, it is within the scope of my 65 invention to set the grinding shoes 16 eccentric and their axes of independent rotation as shown in Figure 3 of the drawings.

By arranging the shoes eccentric to their centers a somewhat planetary movement of 70 the shoe will develop to maintain the rouge face of the plate of glass in uniform shape or layer, thus tending to spreading the rouge, which is distributed upon the surface of the glass and has a tendency to become 75 hard on its face. In other words, if the shoes are supported in the form of eccentrics, they will have a tendency to maintain a uniform spread of the rouge and prevent it from accumulating or caking at any spot 80 upon the surface of the glass.

I claim:

1. A grinding and polishing machine having a main shaft, a master head revoluble therein, a fixed master gear positioned above the head, a plurality of vertically disposed spindles journalled on the master head and in gear connection with the master gear wheel, auxiliary heads carried by the spindles, groups of grinding and polishing 85 shoes carried by each of said auxiliary heads and a series of auxiliary grinding and polishing shoes carried by the master head, the same being circumferentially positioned at a point approximating the maximum 90 circle traveled in by the shoes of the groups of grinding and polishing shoes. 95

2. A grinding and polishing machine comprising a longitudinal traveling carriage adapted to receive a plate of glass, a rotary grinding mechanism fixedly positioned above the table and a series of groups of grinding and polishing shoes, means for imparting a planetary motion to the same and auxiliary grinding and polishing shoes interposed between the outer shoes of each group, the same being provided with means for imparting a rotary motion thereto. 100

In testimony that I claim the foregoing I have hereunto set my hand at Butler, in the county of Butler and State of Pennsylvania. 105

JAMES CARRIE.
